[57] CLAIM

The ornamental design for an automobile, as shown and
described.

DESCRIPTION

FIG. 1 is a left side elevational view of an automobile
showing my new design;

FIG. 2 is a top plan view thereof;

FIG. 3 is a front elevational view thereof;

FIG. 4 is a rear elevational view thereof;

FIG. 5 is a front elevational view of an automobile
showing a second embodiment of my new design, the
sole difference being the use of two rear wheels instead
of one; and

FIG. 6 is a rear elevational view of FIG. 5.
